UNITED STATES PATENT OFFICE.

KARL K. SCHULZ, OF CHICAGO, ILLINOIS, ASSIGNOR TO CYCLE WASHING MACHINE COMPANY, OF CHICAGO, ILLINOIS, A CORPORATION OF ILLINOIS.

OPERATING MECHANISM FOR WASHING-MACHINES.

1,285,418.

Specification of Letters Patent. Patented Nov. 19, 1918.

Application filed December 17, 1915. Serial No. 67,316.

To all whom it may concern:

Be it known that I, KARL K. SCHULZ, a citizen of the United States of America, and resident of Chicago, Cook county, Illinois, have invented a certain new and useful Improvement in Operating Mechanism for Washing-Machines, of which the following is a specification.

My invention relates to improvements in laundry apparatus, and more particularly to combination washing machines and wringers, and one of the objects is to provide an improved apparatus of this character which will be simple, durable and reliable in construction, and effective and efficient in operation.

Another object of my invention is to so associate a washing machine and wringer that a single source of power is capable of driving both or either mechanisms at will, and so that the wringer may be used at various angles or in different positions with respect to the washing machine.

Other objects of my invention will appear hereinafter.

My invention consists in the features of novelty exemplified in the construction, combination and arrangement of parts hereinafter described, shown in the accompanying drawings, and more particularly pointed out in the accompanying drawings.

Referring to the accompanying drawings:

Figure 1 is a view in elevation of a washing machine and wringer structure embodying my invention;

Fig. 2 is a top plan view of the structure shown in Fig. 1;

Fig. 3 is an enlarged detail section substantially on the line 3—3 of Fig. 2;

Fig. 4 is a transverse detail view on the line 4—4 of Fig. 3;

Fig. 5 is an enlarged detail view partly in section on the line 5—5 of Fig. 2;

Fig. 6 is an enlarged detail section on the line 6—6 of Fig. 5;

Fig. 7 is a detail view, partly in section, of the transmission shaft, universal couplings therein, and the gears associated therewith;

Fig. 8 is an enlarged detail on line 8—8 of Fig. 2; and

Fig. 9 is a detail section of an interlock on line 9—9 of Fig. 8.

The washing machine which I have shown

in the drawings and which embodies my invention comprises generally a tub A supported upon a substantially rectangular platform or table having a number of legs B disposed at the four corners of the platform but this may be of any suitable construction 60 for the purpose. The tub is preferably round and has a cover C which is hinged at 1 so that it may be raised into a position to permit access to the interior of the tub, a bumper or stop 2 being provided to limit 65 the outward movement. Extending up alongside of the tub is a casting or other suitable member 4, the lower end of which supports a train of gears through which power is transmitted to the washing machine 70 and wringer. There is a pulley 5 around which a belt may be extended, this belt being driven by a motor or other suitable source of power (not shown) for driving the mechanisms. This pulley 5 is supported on 75 a shaft 6 in suitable bearings in the lower end of the casting 4. The shaft 6 carries a small pinion 7 which drives a larger gear 8, the larger gear being mounted on the shaft 9 supported in bearings in a lateral extension 80 9^a at the lower end of casting 4. The extension 9^a has its end attached to the adjacent leg B to render the structure firm and substantial. The gear 8 has connected to it a pitman or connecting rod 10 which extends 85 upward to the top portion of the tub where it connects to one arm 11 on the bell crank lever. The other arm 12 of the bell crank is formed as a segment and is provided with teeth on its periphery which mesh with a 90 small gear 12^a on the outer end of a horizontally disposed shaft 13 whereby as the bell-crank is rocked by the pitman 10 it imparts a rocking or oscillating movement to the shaft 13. This shaft has bearings in a 95 casting or bearing member 14 which is fastened to the cover C. The small gear 12^a with which the segment arm 12 meshes is enclosed in a casing 15 which protects the operator from injury, and this casing also extends over and incloses the teeth of the segment arm 12, but it is not connected to the segment or to the casting 4 so as not to interfere with the raising and lowering of the cover at will. The act of raising the cover C however separates the gears so as to disconnect the washing machine mechanism from its driving power and the lower-

ing of the cover again places these gears in mesh. On its inner end the rock shaft 13 carries a beveled gear 13^a which meshes with and drives a similar gear 13^b on the dolly 5 shaft 16 of the machine. This dolly shaft is centrally located substantially in the vertical axis of the tub and there is provided suitable bearings for supporting the dolly shaft in position. The dolly in the lower 10 portion of shaft 16 is not shown and needs no particular description. The gears 13^a and 13^b are inclosed in a suitable casing 17 so as to protect the operator.

Referring to Figs. 2, 5 and 6 it will be seen 15 that the upper end of the casting member 4 has formed integrally with it a curved lug 20 which rises above the top of the tub and is positioned adjacent the edge of the cover. This lug is undercut, as at 21, to form a 20 hook, and the surface portion 22 of this member is curved or beveled off so as to form a sort of cam. The casting 14 on the cover carries a horizontally swinging latch lever 23 which is pivoted at 24, and the outer end, 25 of this lever is adapted to engage the undercut 21 of lug 20 so as to lock the cover firmly in position and prevent the vertical separation of the gear 13^b from gear 13^a incident to the transmission of power through these 30 gears. To release or unlock the cover it is simply necessary to swing the lever 23 laterally until it clears the undercut portion 21 when the cover may be raised as desired. At the rear end of the lever 23 beyond its pivot 35 there is a small spring 25 interposed between the lever and a lug on the casting 14, suitable sockets being provided in both members for holding the spring. This spring acts on the latch lever 23 to yieldingly urge 40 or retain it in locking position. The cam or rounded-off portion 22 of the lug 21 is provided so that in lowering the cover the outer end of the latch lever will ride off of the lug 21 and then snap into engagement with the 45 undercut portion 21. This relieves the operator from the necessity of manipulating the latch 23 when the cover is closed. In order to take up any lost motion in a vertical direction between the latch lever 23 50 and the undercut portion or hook 21 I provide it with a vertical disposed thumb screw 26 which is adapted to bear against a lug 27 on the casting 14 after the lever has moved into its locking position, thus the operator 55 after the latch lever is in locking position may set the parts up tight by giving the thumb screw a turn or two and thus prevent any rattling or separation of the gears 13^a and 13^b. The cover may also be provided 60 with the usual lock or latch 28 which may be of any suitable type and needs no particular description.

The locking structure just described will effectively take care of the vertical thrust 65 tending to separate or displace the gears 13^a

and 13^b but it will be understood that in a power transmitting structure of this character there is considerable strain on the parts and it is necessary to overcome this condition not only while the gears are in mesh 70 but while they are being connected or disconnected when the cover is lowered or raised. For these reasons I provide a notch or slot 20^a in the member 20 which is adapted to be engaged by a lug or projection 20^b carried 75 by the casting member 14. This lug is formed integrally with the casting 14 and projects beyond the end thereof and in this construction it rises high enough to form a bearing for the shaft 13. The vertical walls 80 of this notch or slot serve as a guide for the lug 20^b and operates to properly align the gears 13^a and 13^b when the cover is raised or lowered. This notch is deep enough to guide or maintain the lug 20^b in its proper position 85 for a portion of its movement after the gears unmash and vice versa the lug enters the notch just before the gears mesh. Any side thrust, when the gears connect or disconnect, will not effect the gears. At one side of the 90 lug 20^b is another smaller lug 20^d (Fig. 9) one face 20^e of which is beveled off and adapted to engage a correspondingly beveled face of slot 20^a. This forms an interlock 95 between the two castings 4 and 14 and effectively prevents the displacement of the casting 4 from 14 in an outward direction.

I provide the structure with a wringer D which is arranged so that it may be driven from the same driving mechanism as the 10 washing machine. This wringer D I mount preferably at one corner of the tub in such manner that it may be shifted to different angular positions with respect to the tub, as shown in dotted lines in Fig. 2. This enables the operator to place the wringer in convenient position so that the clothes may be passed to the wringer from the washing machine tub or from the rinsing to the bluing tubs which are usually placed adjacent 11 the washing machine. The shaft 9, upon which the gear wheel 8 is mounted, is connected to another shaft 30 by means of the universal joint E. This universal joint may be of any suitable type but in the structure 1 shown in the drawings (Fig. 7) it consists of a socket member 32 which is rectangular in section and which is fastened to the end of the shaft 9. Fitting in this socket is a member 33 which is fastened to the end of the 1 shaft 30 and which is square or substantially so to conform with the interior of the socket member 32. The edges 34 of said member 33 are rounded off, however, so that it will have a universally angular movement with 1 respect to the shaft 9 and at the same time be maintained in a driven relation to the shaft 9. The shaft 30 extends angularly beneath the tub to the opposite corner thereof, this end of the shaft being provided with a bear-

ing 35 secured to the under side of the tub. The opposite end of the shaft 30 drives a vertical shaft 36 through a pair of beveled gears 37 and 38 connected to the shafts 30 and 36 respectively, another universal joint E' similar to E being provided to allow for inaccuracies in manufacture and assembling of parts. This vertical shaft 36 extends upwardly vertically and both it and the shaft 30 are journaled in a bracket F secured to one of the legs B. This leg B extends upwardly to the top of the tub and carries a hollow tongue member 40 which extends above the top of the tub. This hollow tongue member is preferably square in section, as shown in Fig. 4. On its upper end the shaft 36 carries a socket member 41 which is fastened on said shaft 36 to rotate therewith. The upper end of the shaft 36 is not confined to a definite position but is free to float, so to speak, within the hollow member 40. This hollow tongue member being somewhat larger than the shaft and its socket member so as to permit of this movement. This free movement of the shaft is provided to prevent the binding of the parts when the wringer is detached from the structure as will later appear. The wringer D may be of any suitable type for this purpose. In this structure I have shown a wringer of the ordinary type having a wooden frame, the structure being preferably so arranged that an ordinary or standard wringer may be employed. This wringer is bolted or otherwise securely fastened at 42 to a wringer support in the form of a casting F, the upper portion of which is formed as a yoke, the yoke members being bridged by an integral portion F'. This casting F has a socket 50 formed in its lower end portion whose cross section is shaped correspondingly to the hollow tongue 40, and this arrangement provides a separable connection between the washing machine frame and the wringer and supports the wringer in the various positions in which it is desired to place it. The wringer may thus be shifted to its several positions by simply lifting the wringer support F clear of the hollow tongue 40 and bodily turning the wringer until it occupies the proper angular position with respect to the machine and the support may then again be slipped over the hollow tongue 40. Fig. 2 shows in dotted lines a wringer positioned to right angles to its normal position shown in full lines. Since the tongue 40 and socket 50 are rectangular in section it serves to lock the wringer against any horizontal swinging movement and will hold the wringer definitely and firmly in its shifted or adjusted position. Of course a number of positions to which the wringer may be shifted may be determined by making the tongue and socket of any suitable polygonal shape. A particular advantage of this arrangement and which constitutes an object of my invention is that for packing and shipping purposes. The wringer may be bodily detached from its support and placed in the tub, thus reducing to a great extent the bulk and over all dimensions of the structure and enable a greater number of machines to be packed in a given space. Furthermore the mere act of placing the wringer in position on its support, will, as later appears, place it in operative connection with its driving mechanism and ready for use. I prefer that the wringer support F be provided with a set screw 51 and a hand wheel for operating said set screw to fasten the support F in any of its adjusted positions, this being clearly shown in Fig. 3. The wringer shaft is connected by a suitable coupling 43 to a short shaft 44 which has bearings in the yoke members of the casting F. This shaft has two beveled gears 45 and 46 loosely mounted to rotate thereon. Each of these beveled gears have clutch teeth 47 and between the gears is a clutch member 48 which is keyed on the shaft 44 to rotate therewith but slides horizontally thereon. This clutch member 48 has teeth at both ends and is shiftable into engagement with the teeth of either of said gears to connect either of the gears to the shaft so that they will drive the shaft. The clutch member is also arranged so that it may occupy a neutral position between the two gears so that neither of them will be connected to the shaft. A suitable clutch shifting yoke member 49 (see Figs. 1 and 3) is pivoted at 55 so that it may be swung in either direction to engage the clutch member 48 with either one of the gears. This clutch shifting member has a handle 56 which carries a spring-pressed pin 57 adapted to engage the small notches or depressions 59^a in the bridge portion F'. These notches correspond to the vertical positions to which the clutch may be shifted and operate in conjunction with the pin to hold the clutch in its shifted position. The two gears 45 and 46 mesh with and are driven by a common gear 60 which is carried on the upper end of a short vertical shaft 61 having bearings in the casting. The lower end of this short shaft 61 projects into the socket 50 of the casting and is adapted to enter the sleeve 41 on the shaft 36. It has a cross pin 62 near its end which is adapted to engage in a transverse notch in the end of the sleeve 41. This arrangement forms a detachable coupling between the two shafts 61 and 36, so that the act of bodily removing the wringer and replacing it in the same or adjusted position operates to uncouple or couple the shafts 61 and 36. The lower end of the shaft 61 is tapered or pointed so that although the shaft 36 and the sleeve 41 have some lateral play within the hollow tongue 40, it will center the shaft 36 and insure the making of the coupling.

Thus the operator in shifting the wringer need not pay any particular attention to the coupling and uncoupling of the shafts 61 and 36. The rotation of the shaft 36 in a constant direction will operate through the medium of the gear 60 to drive the gears 45 and 46 in opposite directions and the operator may by shifting the clutch member 48 cause the wringer shaft to be driven in either direction of rotation as desired.

What I claim as my invention is:

1. The combination of a support, a movable member on said support, driven mechanism mounted on said member and movable therewith to different positions, driving mechanism for actuating the driven mechanism adapted to be brought into operative connection therewith in the act of moving said member to one of its positions, and means for relatively positioning the driving mechanism and driven mechanism for proper connection just prior to the actual connection thereof.
2. The combination of a support, a movable member on said support, driven mechanism mounted on said member and movable therewith to different positions, driving mechanism for actuating the driven mechanism adapted to be brought into operative connection therewith in the act of moving said member to one of its positions, means for relatively positioning the driving mechanism and driven mechanism for proper connection just prior to the actual connection thereof, and a lock for maintaining said

mechanism against relative movement while said connection is made.

3. In a washing machine, a driving gear and a driven gear, a tub, a movable cover for the tub, a member mounted on said tub and carrying said driving gear, a second member mounted on said cover and carrying said driven gear, one of said members being provided with a notch having inclined walls, and a projection on the other of said members adapted to engage with said notch when said cover is closed to thereby guide said driven gear into proper engagement with said driving gear.

4. In a washing machine, a driving gear and a driven gear, a tub, a movable cover for the tub, a member mounted on said tub and carrying said driving gear, a second member mounted on said cover and carrying said driven gear, one of said members being provided with a notch having inclined walls, a projection on the other of said members adapted to engage with said notch when said cover is closed to thereby guide said driven gear into proper engagement with said driving gear, and a spring lock for automatically locking said cover against movement.

Signed by me at Chicago, Illinois, this 27th day of November, 1915.

KARL K. SCHULZ.
